DESIGN FOR A CIGARETTE BOX OR SIMILAR ARTICLE

Stephen E. Toussaint, Glen Ellyn, Ill.

Application April 5, 1945, Serial No. 118,870

Term of patent 14 years

(Cl. D85—2)

To all whom it may concern:

Be it known that I, Stephen E. Toussaint, a citizen of the United States, residing in the county of Du Page and State of Illinois, have invented a new, original, and ornamental Design for a Cigarette Box or Similar Article, of which the following is a specification, reference being had to the accompanying drawings, forming a part thereof.

In the drawings,

Fig. 1, showing my new design, is a perspective view of my cigarette box or similar article;
Fig. 2 is a direct side elevational view thereof;
Fig. 3 is a top plan view;
Fig. 4 is a front view.

I claim:

The ornamental design for a cigarette box or similar article, as shown.

STEPHEN E. TOUSSAINT.
